UNITED STATES PATENT OFFICE.

GUSTAVE LEVIN, OF BOGALUSA, LOUISIANA.

SHOE-BOX ATTACHMENT.

Application filed March 26, 1925. Serial No. 18,544.

To all whom it may concern:

Be it known that I, GUSTAVE LEVIN, a citizen of the United States, residing at Bogalusa, in the parish of Washington and State 5 of Louisiana, have invented a new and useful Shoe-Box Attachment, of which the following is a specification.

This invention has reference to an indicating card especially designed for use in connection with boxes employed as containers 10 for shoes, shirts, or other wearing apparel.

The primary object of the invention is to provide a card of this character which may be readily and easily positioned within a 15 box, a portion thereof extending through one wall of the box, where it will be clearly visible to the salesman, enabling the salesman to determine the character of the articles contained in the box as to size, cost, 20 shape and color.

A still further object of the invention is the provision of means to facilitate the removal of the box from a shelf, eliminating the necessity of a person grasping the box 25 by the overhanging flange of the cover thereby insuring against tearing the cover while being removed.

Another object of the invention is to provide a card system wherein a day's sales may 30 be checked, and the number of articles contained in the box recorded.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 40 within the scope of what is claimed, without departing from the spirit of the invention.

Referring to the drawing:

Figure 1 is an elevational view, partly in 45 section, illustrating a box supplied with a card constructed in accordance with the invention.

Figure 2 is a fragmental plan view thereof, the cover being broken away illustrating 50 the card in plan.

Figure 3 is a plan view of one of the cards.

Figure 4 is a plan view of a modified form of card.

Referring to the drawing in detail, a box 55 for containing shoes, is indicated by the reference character 5, the box being constructed

of the usual and well known material such as card board or the like, which is cut to provide a tongue 6, the tongue being disposed substantially intermediate the side edges of 60 the box and in spaced relation with the end of the box adjacent thereto.

The box 5, is also formed with a slot 7 disposed adjacent to the bottom of the box, which slot accommodates the reduced portion 8 or finger piece of the card in a manner as clearly shown by Figure 1 of the drawing, so that when the card is positioned in a box, the portion 8 thereof will extend through the box where it may be readily grasped by a 70 salesman, or person removing the box from a shelf.

The card is indicated generally by the reference character 9 and as shown, is ruled with horizontal lines 10 and vertical lines 75 11, the vertical lines 11 dividing the card into lateral spaces while the horizontal lines 10 divide the lateral spaces into spaces to receive certain data such as date, cost, sale price, or other valuable information to facilitate the checking up of sales.

It is contemplated to stamp or otherwise provide the shape, or possibly the color of the article contained in the box, on the extended portion 8 of the card, so that the 80 salesman may at a glance, determine the character of the article contained in the box.

As illustrated by Figure 2, the reduced portion of each card is constructed in such a way that shoulders 12 will be provided, 90 which shoulders engage the front wall of the box at a point adjacent to the bottom thereof, so that when the reduced portion is pulled by the salesman, the box will be moved or slid from its position on the shelf, 95 where the contents thereof may be readily removed.

It will also be noted that due to the construction of the tongue 6, the card is securely locked within the box and prevented 100 from moving inwardly, to the end that the reduced portion will be in an exposed position at all times, to accomplish its purpose.

In the form of the invention as shown by Figure 3, a slight variation as to the shape 105 of the reduced portion is illustrated, the reduced portion being indicated at 13, and shown as circular. A facing such as indicated at 14 and embodying a small portion of the type of cloth or shirt, should the device be employed for containing shirts, is secured to the reduced portion, so that a 110

salesman may determine the pattern of the goods in the box.

A still further type of card is indicated by Figure 4 and includes a body portion 15, 5 which may be ruled to contain the necessary data relating to the article contained in the box, and a finger piece indicated at 16 which is substantially triangular in formation.

While I have illustrated this device employed in connection with a shoe box, it is 10 to be understood that the card may be employed with equally as good results on boxes containing articles of all types and characters.

15 It might be further stated that when the contents of a box become depleted, the card may be removed and filed in a suitable container for this purpose, thereby providing a check on the articles sold and at the same 20 time providing means whereby the salesman or owner may determine the empty boxes so that they may be again filled.

I claim:—

1. In combination with a display box 25 having an upwardly extended tongue stamped from the bottom thereof and having a slot formed adjacent thereto, an indicating card comprising a body portion adapted to be fitted in the box and disposed between 30 the tongue and front wall of the box, a reduced portion forming a part of the body portion and extended through the slot, and said reduced portion providing a hand grip.

2. In combination with a display box having 35 an upwardly extended tongue stamped from the bottom of the display box, said display

box having a slot formed in its forward wall, a display card including a body portion, said body portion adapted to be positioned under the tongue, the forward edge of 40 said body portion adapted to engage the front wall adjacent to the slot, and a reduced portion forming a part of the body portion and adapted to extend through the slot to be engaged by the fingers of the person removing a box from a shelf. 45

3. In combination with a display box having a tongue extending upwardly from the bottom thereof, the front wall of the box having an opening, an indicating card positioned under the tongue and having shoulders adapted to engage the front wall of the box, and said reduced portion adapted to extend through the slot of the head to provide a finger hold. 50 55

4. In combination with a display box having a tongue extending upwardly from the bottom thereof, said tongue being spaced from one end of the box, said box having a slot formed in the forward wall thereof, an 60 indicating card including a rectangular body portion adapted to be positioned in the box, the forward edge of the body portion contacting with the front wall of the box, said tongue adapted to overlie the body portion, and an extension forming a part of the body portion and positioned within the slot. 65

In testimony that I claim the foregoing as my own, I have hereto affixed my signature.

GUSTAVE LEVIN.
